UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,868, dated March 11, 1884.

Application filed January 22, 1884. Term of patent 3½ years.

To all whom it may concern:

Be it known that I, OTTO HEINIGKE, of New Utrecht, in the State of New York, have invented a new and original Design for Carpets, 5 of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The prominent features of the design are the

drooping clusters of long flag-like leaves occurring at intervals and in various combinations over the face of the design, and the broad vein-like connections that irregularly traverse it. The whole design is closely filled in, and the leaf and small scattered flower groups are thickly massed over its face. The effect of the design as a whole is a general effect.

I claim—

The design for a carpet, substantially as 25 shown and described.

OTTO HEINIGKE.
